UNITED STATES PATENT OFFICE.

SILAS B. HAZEN AND GEORGE L. VAN GORDER, OF WINAMAC, INDIANA.

DOOR-CHECK.

SPECIFICATION forming part of Letters Patent No. 281,504, dated July 17, 1883.

Application filed May 14, 1883. (No model.)

To all whom it may concern:

Be it known that we, SILAS B. HAZEN and GEORGE L. VAN GORDER, both of Winamac, in the county of Pulaski and State of Indiana, 5 have invented a new and Improved Door-Holder, of which the following is a full, clear, and exact description.

The object of our invention is to provide a new and improved device of simple construction for holding doors, swinging screens, gates, &c., open and in the desired position.

The invention consists in a wedge-shaped frame of metal plates or spring-wire, which frame is provided at the bottom of the incline 15 with an upwardly-inclined spring-catch for holding the door open, and at the opposite end it is provided with downwardly-projecting prongs for keeping the holder in place.

Reference is to be had to the accompanying 20 drawings, forming part of this specification, in which similar letters of reference indicate corresponding parts in all the figures.

Figure 1 is a perspective view of a door held by means of our improved door-holder. Fig. 25 2 is a perspective view of our improved door-holder. Fig. 3 is a perspective view of a modification of the same. Fig. 4 is a longitudinal elevation of our improved door-holder, showing the manner in which it holds the door.

30 A spring-frame, A, made of wire, as shown in Figs. 1, 2, and 4, or of a metal plate, as shown in Fig. 3, is provided at one end with pointed downwardly-projecting prongs *a*, from the upper ends of which the wire or plate is 35 inclined downward at an angle of about twenty to twenty-five degrees, and at the lower end of the inclined part *b* the wire or plate is bent over and is inclined upward, and about parallel with the part *b* and at about the middle of 40 the latter the end *d* of the upwardly-inclined part *c* is bent downwardly slightly or beveled. The spring-frame A is placed in the floor within the arc described by the outer swinging edge of the door in such a manner that the 45 lower end of the downwardly-inclined part *b* projects toward the closed door and the points

of the prongs *a* rest on the floor. If the door B is swung open, its lower edge meets the inclined part *c* of the frame A and slides along the same and depresses it, and when the lower edge of the door has passed over the upper end of the inclined part *c* the said upper end snaps upward and rests against the lower part of the door, as shown in Fig. 4. The inclined part *b* prevents the door from opening farther, 55 and the part *c* prevents it from closing. The door can thus be held in any desired position by means of our improved door-holder. If the door is to be closed, the upper end of the part *c* is depressed by means of the foot, thus releasing the door. The pressure on the frame A forces the points of the prongs *a* sufficiently to hold the frame A in place and prevent slipping of the same. The holder does not injure the door nor the floor, and can be adjusted and 60 removed very easily and rapidly. The frame has a wedge shape, provided at its lower end with a spring-catch for holding the door. The holder can be used for holding swinging doors, 65 screens, gates, &c., in place.

Having thus described our invention, what we claim as new, and desire to secure by Letters Patent, is—

1. A spring-frame for holding doors, provided with downwardly-projecting prongs *a*, 75 a downwardly-inclined part, *b*, and an upwardly-inclined part, *c*, having its upper end, *d*, beveled or bent down, substantially as herein shown and described, and for the purpose set forth.

2. A door-check made of a wire or metallic-plate frame, provided at one end with prongs, from the upper ends of which a part is inclined downwardly, then bent over at its lower end and inclined upwardly, as shown and de- 85 scribed.

SILAS B. HAZEN.

GEORGE L. VAN GORDER.
